UNITED STATES PATENT OFFICE

ARTHUR VON FRANKENBERG, OF NEW YORK, N. Y., ASSIGNOR TO FRANKART, INC., OF NEW YORK, N. Y., A CORPORATION OF NEW YORK

DESIGN FOR AN ASH TRAY OR SIMILAR ARTICLE

Application filed October 9, 1930. Serial No. 37,207. Term of patent 7 years.

To all whom it may concern:

Be it known that ARTHUR VON FRANKENBERG, citizen of the United States, and resident of New York city, in the county of New York and State of New York, has invented a new, original, and ornamental Design for Ash Trays or Similar Articles, of which the following is a specification, reference being had to the accompanying drawing, forming part thereof, in which the figure is a perspective view of the ash trays embodying my new design.

The side of the design opposite to that shown in the drawing shows the rear of the

figure, the base and the trays being similar in the front and rear.

Referring to the drawing and particularly to the dominant features of the design, the latter are seen to comprise the figure of a dancing girl and one or more ash trays interposed between the torso and leg portions to simulate the ballet skirts of the dancer.

I claim:

The ornamental design for an ash tray or similar article, substantially as shown and described.

Dated, New York city, October 6, 1930.
ARTHUR VON FRANKENBERG.
